MULTICHANNEL SECRET COMMUNICATION SYSTEM

Paul Saylor, Jr., San Antonio, Tex., assignor of
fifty percent to Frederick H. Hagner, San Antonio, Tex.

Application May 1, 1936, Serial No. 77,435

4 Claims. (Cl. 179—1.5)

This invention relates to a multi-channel secret communication system, and has for one of its objects the production of an efficient means for setting up, through the medium of a sending unit or sending units, a carrier wave having a characteristic form which is modulated at frequencies distinguishable to my selective receiving unit only, and which is normally indistinguishable to a conventional receiving system.

10 A further object of this invention is the production of a method of transmitting a carrier wave having a characteristic form at indistinguishable frequencies, then receiving the indistinguishable frequencies and re-forming the indistinguishable frequencies so that they are rendered distinguishable.

Another object of this invention is the production of a multi-channel communication system embodying a sending unit and a receiving unit, 20 wherein a multi-channel communication may be maintained between the sending and the receiving units over a single carrier wave.

Still another object of this invention is the production of an improved electro-vibrating condenser for creating frequency modulation to provide remote control for the signal pick-up.

Other objects and advantages of this invention, as well as the objects and advantages of certain detail portions of the system will appear 30 throughout the following specification and claims.

As an illustration of the principle embodied in the present invention, a simple explanation is given as follows:—

35 When an orchestra or band is making a broadcast, every individual instrument in the orchestra or band sets up a characteristic frequency or group of frequencies in the nature of sound waves, and these frequencies or sound waves are gathered into the microphone and through suitable mechanism modulated into one carrier wave as a complete unit of sound. The carrier wave is picked up by a receiver and through the medium of the speaker the sound is received by the ear 45 of the listener where the complete unit of sound is broken up into its component parts and enables the listener to distinguish the individual sound or voice of the individual instruments of the orchestra or band which is being broadcast. By 50 keeping this fact in mind, it should be understood that a similar result is accomplished in a different way through the medium of my system. Separate groups of frequencies are produced out of range of the human ear, which frequencies are 55 far enough apart from each other to avoid inter-

ference, and which frequencies have a proper relationship to the frequencies picked up by the microphone, all of the frequencies being sent out over the same carrier at the same time, the carrier wave then being received and finally broken up and fed to separate distinct channels through selected speakers, whereby a number of separate and distinct signals transmitted may be secretly and individually transmitted and received through the speakers at the same time. The 10 advantage of my system is to broaden the spectrum in an indirect way of radio frequency broadcasting or transmission, involving all types of electrical signal impulses. This is accomplished by having a plurality of signal input 15 sources that do not interfere with each other and a receiver having a plurality of reproducers which do not interfere with each other.

As a further example, when a program, such 20 for instance as an orchestral broadcast, is gathered into a microphone, the composite sound of the various voices of the individual instruments is received by the microphone. In my system, individual microphones will pick up individual 25 program broadcasts and feed these broadcasts to a station where they will be transmitted over a single composite carrier wave. In the case of a single broadcast where the voices of the instruments are gathered into a single microphone and transmitted in the well known manner, this composite 30 tone or sound is received and reproduced by a single speaker and the human ear will pick up the sound enabling the listener to separate the voices of the various instruments of the single broadcast. In my system, the various individual 35 or separate broadcasts picked up by the separate microphones, after being transmitted by a single carrier wave, will be received through the medium of the single carrier wave and then separated 40 and distributed to separate and distinct speakers by the separate and individual microphones.

In the drawings:

Figure 1 is a diagram of the frequency modulated oscillator illustrating the circuits for one 45 signal channel and employing my new electro-vibrating condenser and showing the audio-amplifiers in conjunction with the condenser;

Figure 2 is a diagram of the amplitude modulated power amplifiers including its exciting crystal controlled oscillator;

Figure 3 is a diagram somewhat similar to Figure 1, and illustrating a group of typical circuits for a second or additional signal channel;

Figure 4 is a diagram of a third signal channel;

Figure 5 is a diagram showing the receiving circuits embodying two separate radio frequency amplifiers, a demodulating stage, a modulating stage, a frequency modulated oscillator, a constant frequency oscillator, and a high gain audio amplifier for one channel of reception;

Figure 6 is a diagram showing a group of circuits for a second or other channel, comprising a modulator stage, a frequency modulated oscillator, a constant frequency oscillator, and a high gain audio amplifier and also another channel which is a high gain amplifier to amplify whatever audible frequencies may be present in the carrier wave itself;

Figure 7 is a diagram of various circuits showing three separate two-stage audio amplifiers and their power unit, each amplifier consisting of an input stage and an output stage, each amplifier also having its separate speaker;

Figure 8 is a general diagram of the receiving circuit, disclosing the wave form that each unit produces;

Figure 9 is a general diagram of the transmitting circuit, disclosing the wave form that each unit produces;

Figure 10 is a diagrammatic view of the electro-vibrating condenser used in connection with my invention;

Figure 11 is a transverse sectional view through the electro-vibrating condenser;

Figure 12 is a top plan view of the electro-vibrating condenser.

By the term "indistinguishable" as used in the following description, it should be understood that the frequencies are other than their natural or original nature. As for instance, when transmitting audible sound, the frequencies are raised beyond the range of the frequencies to which the human ear may respond, thereby producing a carrier wave that even if it is received, no ordinary audio equipment, loud speakers, etc. will respond to it.

By referring to the drawings, it will be seen that I employ a sending system, as shown in Figure 9, and a receiving system, as shown in Figure 8. The sending system is shown in detail in Figures 1, 2, 3 and 4, whereas the receiving system is shown in detail in Figures 4 to 6, inclusive. These units may be multiplied at the will of the operator, and for the purpose of explaining the circuits and system as well as the method employed in connection with the present invention, it is only necessary to explain in detail the typical circuits, method and system employed when using one sending unit and one receiving unit.

Attention is invited particularly to Figure 1, wherein it will be noted that 15 designates a 76-type tube and 16 designates a 42-type tube. A microphone or signal pick-up 17 is grounded, as at 20, and the other terminal of the microphone 17 is connected to a microphone battery 21, the battery 21 being in turn connected in series with the primary of a microphone transformer 18. The secondary of the microphone transformer 18 is connected in series with a gain control potentiometer 19, one terminal of the potentiometer 19 being grounded, as at 22. The primary, and also the secondary of the transformer 18, are grounded as at 23. The circuit just described constitutes an amplifying circuit for the microphone 17, the elements of which are connected in series. The potentiometer 19 is connected to the control grid 24 of the tube 15 by means of an electrical connection 25. The plate 13 of the tube

18 is connected with the primary of the inter-stage transformer 26, the other end of the primary being connected in series with the resistor 27, this resistor 27 being also connected to the supply line of the 250 volt power unit 28. A by-pass condenser 29 is placed between the ground and the primary of the transformer 26 which is connected to the resistor 27. The secondary of the transformer 26 is connected in series with the control grid 30 of the tube 16 the other end of the transformer being grounded and the screen grid 31 is connected to the supply line of the power unit 28. The plate 32 is connected in series to the primary of an inter-stage transformer with a ratio of 1:1. The other side of the primary winding of the transformer 33 is connected to the supply line of the power unit 28. The cathode of the tube 16 is connected to the resistor 34, the other side of the resistor 34 being grounded. A condenser 35 is connected in parallel with the resistor 34. The tube 15 is provided with a cathode connection embodying a resistor 36 and a condenser 37 similarly connected with respect to bias circuit of the tube 16. The filaments of both of the tubes 15 and 16 are connected in parallel with the secondary of the step down transformer 38 and the primary is connected in parallel with the alternating current supply 39. The circuits above described constitute a conventional two-stage audio amplifier.

The secondary of the inter-stage transformer 33 is connected in parallel with the electro-magnet 40 of the electro-vibrating condenser 41 and this condenser will be described as to its detail structure in the following:

An oscillator circuit is employed using a 59-type tube 42. The screen grid 43 and the suppresser grid 44 of the tube 42 are connected with a tap on a resistor 45. One side of the resistor 45 is grounded, the other side being connected to the supply line of the power unit 28. A by-pass condenser 46 which is grounded is connected to the resistor 45, and also to the supply line of the power unit 28. The plate 47 of the tube 42 is connected to a radio frequency choke 48 which in turn is connected to the supply line of the power unit 28. The control grid 49 of the tube 42 is connected to one side of the condenser 50 and to the radio frequency choke 51, which in turn is connected to a resistor 52, the other side of the resistor being grounded. The other side of the condenser 50 is connected to an inductance coil 53, and to one side of a variable tuning condenser 54 and also to the stationary plate terminal 55 of the electro-vibrating condenser 41, which condenser 41 will also be described structurally in the following. The opposite side of the inductance coil 53 is grounded and a tap approximately one-third of the distance from the ground is attached to the coil and forms a connection with the cathode of the tube 42. The filament of the tube 42 is connected in parallel with the secondary of the step down transformer 56 and the primary is connected in parallel with the alternating current supply 57. The vibrating diaphragm 58 of the electro-vibrating condenser 41 is connected to the casing thereof, which casing is also grounded.

A coupling coil 59 connects to the negative side of a bias battery 60, the positive end of which is grounded. The opposite side of the coil 59 leads to the connecting wire 61 (note Figure 2), which goes to the suppresser grid 62 of the tube 63 which is of the type RK20.

Figure 3 discloses a second two-stage audio

amplifier coupled with a frequency modulated oscillator including a second electro-vibrating condenser.

The various parts are identical in every respect in Figure 3, including the circuits, to that shown in Figure 1, and for the purpose of identifying the parts, the similar parts are designated by the same numerals with the addition of the letter "a". It should be noted, however, that the bias battery 60a and the coupling coil 59a in the circuits shown in Figure 3, are connected to the wire 63 which passes to the suppresser grid 64 of the tube 65, which tube is also of the RK20 type.

Figures 1 and 3 illustrate the circuit connections for two or more signal pick-ups within the transmitting system.

Attention is now invited particularly to Figure 2 where it will be noted that C designates a conventional type of crystal controlled oscillator. This oscillator embodies a tube 66 which may be of the 59-type. The screen grid 67 and the suppresser grid 68 are connected to the tap or the resistor 69, one side of the resistor 69 being grounded and the other side being connected to the supply line of the 500 volt power unit 70, the power unit 70 being grounded as shown. A by-pass condenser 71 having one side grounded is connected at its other side to the screen and suppresser grids 67 and 68 of the tube 66. A by-pass condenser 72 having one side grounded, is in turn connected on its opposite side to the supply line of the 500 volt power unit 70. The plate 73 of the tube 66 is connected to the tank inductance coil 74, the other side of which is connected to the supply line of the power unit 70. A tuning condenser 75 is connected in parallel with the tank coil 74. The control grid 76 of the tube 66 is connected to a radio frequency choke 77 and to a crystal 78 which crystal is grounded at its opposite side and the opposite side of the choke 77 is connected to a bias resistor 79, the opposite side of which is grounded, and a condenser 80 is connected in parallel to the bias resistor 79. The cathode of the tube 66 is grounded and the filament of the tube 66 is connected in parallel to the secondary of the step down transformer 81, the primary of the transformer 81 being connected in parallel to the alternating current supply 82. A coupling coil 83 is connected at one side to the tuning condenser 84 which condenser 84 is connected at its opposite side to the plate 73 of the tube 66, the opposite side of the coil 83 being connected to the wire 11 which feeds a parallel circuit to all of the control grids 85, 86 and 87 of the tubes 12, 65, and 88.

Radio frequency power amplifier utilizing pentode tubes

This circuit utilizes tubes 12, 65 and 88. All of the screen grids 89, 90 and 91, are connected in parallel to the radio frequency choke coil 92, the other side of which is connected to the tap on the resistor 93 and one side of the resistor 93 is grounded. The opposite side of the resistor 93 is connected to the 1000 volt supply line of the power unit 94 which power unit is also grounded. The by-pass condenser 95, one side of which is grounded, has the other side connected to the choke coil 92. The control grids 85, 86 and 87 are also connected to the radio frequency choke 96, the other side of which choke is connected to the negative terminal of the bias battery 97 out of which battery the positive terminal is grounded. The plates 98, 99 and 100 are connected

in parallel and to the radio frequency choke 101, the other side of the radio frequency choke being connected to the 1000 volt supply line of the power unit. A by-pass condenser 102 having one side thereof grounded, is connected at its opposite side to this 1000 volt supply line 103. A blocking condenser 104 has one side connected to the plates 98, 99 and 100 and has its opposite side connected to the tank inductance coil 105 and also to the variable tuning condenser 106 the opposite side of the condenser 106 being grounded. The other side of the inductance coil 105 is connected to the transmitting antenna 107 and also to one side of the variable condenser 108, the opposite side of the condenser being grounded. The filaments of the tubes 12, 65 and 88 are connected in parallel with the secondary of the step down transformer 109 which has a center tap grounded in the conventional manner. It should be noted that two radio frequency by-pass condensers 110 and 111 are connected in series with each other, the connection common to both condensers being grounded. These condensers that are in series are connected in a parallel circuit with the filaments. The primary of the step down transformer 109 is connected in parallel with the alternating current supply 112.

The frequencies produced by the oscillators in Figures 1 and 3 are in the neighborhood of 100 k. c. or so. However, it is not desired to limit my system to this range of frequencies.

Two signal pick-up channels have been described above, and the following is a description of a third signal pick-up channel. The two previously described signal pick-up channels have means for rendering the frequencies indistinguishable and the following signal pick-up circuit produces conventional distinguishable frequencies for modulation upon the power amplifier, the circuits being illustrated in detail in Figure 4.

Attention is now invited in detail to Figure 4 which illustrates a diagram showing a conventional two-stage audio amplifier having the same characteristic elements as defined with respect to the conventional audio two-stage amplifier in Figure 1, the similar parts being designated by the same numerals having an additional letter designation "b". The difference is that the secondary of the inter-stage transformer 33b has one side connected to the negative terminal of the bias battery 60b, the positive terminal of which is grounded. The other end of the secondary 59b of this transformer 33b is connected to the wire 113. The wire 113 is connected to the suppresser grid 114 of the tube 88, note Figure 2.

In this transmitting unit, I have illustrated three distinct signal pick-up channels, one channel being illustrated in Figure 1, a second in Figure 3, and a third in Figure 4. It should be understood that the signal pick-up channel illustrated in the diagram in Figure 4 produces a distinguishable frequency whereas the circuits illustrated in detail in Figure 1 produces a still further indistinguishable frequency. The factor which determines the characteristic frequency 65 nature of the indistinguishable frequency is the variable tuning condenser 54 in the circuit in Figure 1, and 54a in the circuit in Figure 3.

In the diagram, as shown in Figures 1 and 3, it will be noted that the electro-vibrating condensers 41 and 41a respectively are included so that the frequencies set up by the oscillators in Figures 1 and 3 may be frequency modulated in accord with each respective signal input at the respective signal pick-up.

The variable condensers 54 and 54a control the characteristic frequency set up by the oscillators in Figures 1 and 3, and the stationary plates 55 and 55a, and vibrating plates 58 and 58a constitute a condenser in parallel with the controlling condensers 54 and 54a. It is a known fact that where condensers are connected in parallel the variation of either will create a change in capacity of both. When this is done, a change in the frequencies characteristics is accomplished and will be specifically different in each of the circuits shown in Figures 1, 3 and 4, thereby permitting three separate messages to be transmitted over the same carrier wave at one time without interference.

Attention is now invited in detail to Figure 5 wherein it will be noted that a condenser 128 is provided, one side of which is connected to the receiving antenna 121, the other side of which is connected to the primary of the antenna coil 122, the other side of the primary of the antenna coil being grounded with one side of the secondary. The opposite end of the secondary of the antenna coil 122 is connected to the control grid 123 of the type 58 tube 124. A condenser 125 is provided and is in parallel with the secondary of the coil 122, one side of the condenser 125 being grounded. The screen grid 126 of the tube 124 connects to the resistor 127, the other side of which is connected to a voltage dividing resistor 128, the other side of the resistor 128 connecting to the 250 volt supply line of the power unit 129, the power unit being also grounded. A by-pass condenser 130 is connected between the cathode of the tube 124 and the screen grid 126 of the tube 124. The suppresser grid 131 is connected to the cathode of the tube 124. A bias resistor 132 has one side connected to the cathode and the other side is grounded. A by-pass condenser 133 is in parallel with the resistor 132. The plate 134 connects to the primary of the radio frequency transformer 135. The other side of the primary connects to the radio frequency choke 136 and the other side of the choke 136 connects to the 250 volt supply line of the power unit. A by-pass condenser 137 connects to the wire between the primary of the radio frequency transformer 135 and the choke 136, the other side of the condenser 137 connecting to the cathode of the tube 124.

The secondary of the radio frequency transformer 135 is connected to the controlling grid 138 of the 58 type tube 139 and the opposite side of the secondary of the transformer 135 is grounded. A tuning condenser 140 is in parallel with the secondary of the transformer 135, the opposite side of the condenser being grounded. The screen grid 141 of the tube 139 is connected to one side of the voltage dividing resistor 128. A by-pass condenser 142 is connected between the screen grid 141 and the cathode of the tube 139. The suppresser grid 143 of the tube 139 is connected to the cathode of the tube 139 and a bias resistor 144 is connected between the cathode of the tube 139 and the ground, a condenser 145 being in parallel with the bias resistor 144. The plate 146 of the tube 139 connects to the primary of the radio frequency transformer 147, the other side of the primary connecting to one side of the radio frequency choke 148, the other side of the choke 148 connecting to the 250 volt supply line of the power unit 129. A by-pass condenser 149 is connected to the wire between the primary of the transformer 147 and the choke 148, the other side of which goes to the cathode of the tube 139. The

filaments of the tubes 124 and 139 are connected in parallel with the secondary of the step down transformer 150, the primary of the transformer being connected in parallel to the alternating current supply 151. The two tubes 124 and 139 and their circuits constitute a conventional radio frequency amplifier.

The secondary of the transformer 147 has one side connected to the diode plates of the type 2B7 tube 152, and also to a tuning condenser 153, the other side of which condenser is grounded. The opposite side of the secondary of the transformer 147 goes to the resistor 154, and the opposite side of the resistor is grounded. A coupling condenser 157 connects to the wire between the secondary of the transformer 147 and the resistor 154 and the opposite end of the condenser 157 connects to the control grid 155 of the tube 152. Condensers 156 and 157 are additional coupling condensers which are connected at one side to the wire between the secondary of the transformer 147 and the resistor 154. The opposite ends of these condensers connect to the wires 158 and 159—note Figure 6. The screen grid 160 is connected to the voltage dropping resistor 161, the other side connecting to the 250 volt supply line of the power unit 129. A by-pass condenser 162 connects between the screen grid 160 of the tube 152 and the ground. The suppresser grid 163 of the tube 152 connects to the cathode of the tube 152 and a bias resistor 164 connects between the cathode of the tube 152 and the ground. A condenser 165 is in parallel with the resistor 164. The plate 166 of the tube 152 connects to the coupling coil 167, the other side of which coil 167 is connected to the radio frequency choke 168, the other side of the choke connecting to the 250 volt supply line of the power unit 129 through the line 169. A by-pass condenser 165 is connected to the wire between the coupling coil 167 and the choke 168, the other side of the condenser being grounded. The tube 162 and the associated circuits constitute a demodulator and a modulator.

One side of the oscillator coil 170 goes to the grid leak resistor 171 and grid leak condenser 172, the opposite sides of each being connected together and to the control grid 173 of the 57 type tube 174. A tuning condenser 175 is in parallel with the oscillator coil 170, one side of the condenser 175 and coil 170 being grounded. The tap on oscillator coil 170 goes to the cathode of the tube 174. The suppresser grid 176 and the screen grid 177 are connected together and to the voltage dropping resistor 178, the other side of which resistor 178 goes to the 250 volt supply line or wire 169 and then to the power unit 129. A by-pass condenser 179 is connected to the screen and suppresser grids 177 and 176 of the tube 174, the other side of this condenser being grounded. The plate 180 of the tube 174 is connected to the coupling coil 181, the other side of which goes to the radio frequency choke 182. The other side of the choke goes to the 250 volt supply line through the line 183 which joins line 169. A by-pass condenser 184 is connected to the wire between the coupling coil 181 and the choke 182, the other side of the condenser being grounded. The tube 174 and its associated circuits constitute a conventional oscillating circuit.

One side of the oscillator coil 186 goes to the grid leak resistor 187 and grid leak condenser 188, the opposite sides of the condenser and resistor being connected together and to the control grid 189 of the tube 57 type 180. The other

end of the oscillator coil 186 is grounded and a condenser 191 is connected in parallel with the coil 186 and this condenser 191 has one side grounded. A tap on the oscillator coil 186 connects to the cathode of the tube 190. The suppresser grid 192 of the tube 190 and the screen grid 193 are connected together and also are connected to the voltage dropping resistor 194 the other side of which resistor 194 connects to the 5 250 volt supply line by the wire 183. A by-pass condenser 195 is connected to the wire between the suppresser and screen grids of the tube 190 and the other side of the condenser 195 is grounded. The plate 196 of the tube 190 goes to the 10 primary of the audio step up transformer 197, the other side of the primary being connected to the radio frequency choke 198, which choke is connected at its other side to the supply line 183. The tube 190 and its associated circuits 15 20 constitute a second conventional oscillating circuit.

The secondary of the transformer 197 is connected at one side to the control grid 198 of the 57 type tube 199, and the opposite end of the 25 primary is grounded and a load resistor 200 is in parallel with the secondary of the transformer 197. The screen grid 201 of the tube 199 is connected to the voltage dropping resistor 202, the other side of which resistor 202 is connected to the 30 supply line 183. A by-pass condenser 203 is connected between the screen grid 201 and the ground. The suppresser grid 204 of tube 199 is connected at one side to the cathode of the tube 199 and a bias resistor 205 is connected at one 35 side to the cathode of tube 199, the other side of which resistor 205 is grounded. A by-pass condenser 206 is in parallel with the resistor 205 and is grounded at one side. The plate 207 of tube 199 is connected to the radio frequency choke 208 and the other side of the choke is connected to the supply line 183. Plate 207 goes to the wire 209—note Figures 4 and 7. A by-pass condenser 210 is connected between the plate and the ground. The filaments of the tubes 174, 152, 40 45 190 and 199 are all connected in parallel with the secondary of the step down transformer 211, the primary of the transformer 211 being in parallel with the alternating current supply 212.

Attention is now specifically directed to Figure 6. The control grid 213 of the 57 type tube 214 is connected to the wire 158. The screen grid 215 connects to the voltage dropping resistor 216, the other side of which resistor 216 goes to the 50 volt supply line 217 of the power unit 218 which power unit is grounded. A by-pass condenser 219 is connected between the screen grid and ground of the tube 214. A suppresser grid 220 of the tube 214 connects with the cathode of the tube 214 and a bias resistor 221 is connected between the cathode of the tube 214 and the ground. A condenser 222 is in parallel with the bias resistor 221. The plate 223 is connected to the coupling coil 224, the other side of the coil being connected to the radio frequency choke 225 which connects to the supply line 217. A 55 by-pass condenser 226 is connected to the wire between the coupling coil 224 and the choke 225, and the other side of the condenser is grounded. One side of the oscillating coil 227 connects to the grid leak resistor 228, and grid leak condenser 229, the other ends of the grid leak resistor and condenser being connected together and to the control grid 230 of the 57 type tube 231. The other end of the oscillator coil 227 is 60 65 70 75 grounded. A tuning condenser 232 is in parallel

with the oscillating coil 227 and is grounded at one side. A tap on the oscillator coil 227 goes to the cathode of the tube 231. The screen grid 233 and the suppresser grid 234 are connected together and go to the voltage dropping resistor 235, the other end of which resistor 235 is connected to the supply line 217. A by-pass condenser 236 is connected to the suppresser grid and screen grid of the tube 231, one side of the condenser being grounded. The plate 237 of the 10 tube 231 connects to the coupling coil 238, the other side of the coil being connected to the choke 239, and the other side of the choke being connected to the supply line 217. The by-pass condenser 240 is connected to the wire between the 15 coupling coil 238 and the choke 239 and is grounded at one side. The tube 214 and its associated circuits constitute a modulating circuit and tube 231 and its circuits constitute an oscillating circuit. 20

An oscillator coil 241 is shown, one side of which goes to the grid leak resistor 242 and the grid leak condenser 243. The opposite side of the grid leak resistor 242 and the condenser 243 are connected together and to the control grid 244 of 25 the 57 type tube 245. The opposite end of the oscillator coil 241 is grounded. A tuning condenser 246 is in parallel with the oscillating coil 241 and one side of the condenser is grounded. A tap on the oscillator coil 241 is connected to 30 the cathode of the tube 245. A screen grid 247 and the suppresser grid 248 are connected together and go to the voltage dropping resistor 249, the other side of which goes to the supply line 217. A by-pass condenser 250 is connected 35 between the screen grid of the tube 245 and the ground. The plate 251 of the tube 245 is connected to the primary of the audio step up transformer 252, the other side of which goes to the radio frequency choke 253 and the other side of which choke 253 goes to the supply line 217. The tube 245 and its circuits constitute a second oscillating circuit. 40

The secondary of the transformer 252 is connected at one side to the control grid 408 of 45 the 57 type tube 254, the other side of the secondary being grounded. A load resistor 255 is in parallel with the secondary of the transformer 252. The screen grid 256 of the tube 254 is connected to a voltage dropping resistor 257, the other side of which resistor 257 is connected to the supply line 217. A by-pass condenser 258 is connected between the screen grid of the tube 254 and the ground. A suppresser grid 259 connects to the cathode of the tube 254. A bias resistor 260 connects to the cathode of the tube 254, the other side being grounded. A condenser 261 is in parallel with the resistor 260 and has one side grounded. The plate 262 of the tube 254 connects to the radio frequency choke 263 and the other side of this choke 263 goes to the supply line 217. The plate 262 is connected to the wire 264—note also Figure 7. A by-pass condenser 265 is connected between the plate 262 of the tube 254 and the ground. This tube 254 and its associated circuits constitute a high gain 55 60 65 70 75 80 85 90 95 100 audio amplifier.

Note particularly Figure 6 in conjunction with Figure 5, where it will be seen that the wire 159 goes to the control grid 266 of the 57 type tube 267. The screen grid 268 goes to a voltage dropping resistor 269, the other side of which goes to the supply line 217. A by-pass condenser 270 is placed between the screen grid 268 of the tube 267 and the ground. A suppresser grid 271

connects to the cathode of the tube 267. A bias resistor 272 is connected to the cathode of the tube 267 and is grounded at one side. A condenser 273 is in parallel with the bias resistor 272. The plate 274 is connected to the radio frequency choke 275. The other side of the choke goes to the supply line 217. The plate 274 goes to the wire 276. A by-pass condenser 277 is connected between the plate 274 of the tube 267 and the ground. The filaments of the tubes 214, 231, 254, 251 and 267 are connected in parallel with the secondary of the step down transformer 278, and the primary is connected in parallel with the alternating current supply 279.

15 Attention is now directed particularly to Figure 7. The wire 280 goes to the coupling condenser 280, the opposite side of which goes to the potentiometer 281, one side of which potentiometer 281 is grounded, and the rotatable 20 arm of the potentiometer goes to the control grid 282 of the 76 type tube 283 and a by-pass condenser 284 is connected between the control grid 282 and the ground. The cathode of the tube 283 connects to the bias resistor 285 of 25 which the other side is grounded and the by-pass condenser 286 is in parallel with the bias resistor 285. The plate 287 of the tube 283 is connected to the primary of the step up audio transformer 288, the other side of which goes 30 to the 300 volt supply line 289, which line 289 goes to the voltage dropping resistor 290. The other side of the resistor 290 goes to the choke 291 and the other side of the choke goes to one leg of the filament of the type 83 tube 292. The 35 filter condenser 293 connects to one side of the choke 291 and the other side of the condenser is grounded, and the condenser 294 is connected to the opposite side of the choke 291 and the other side of the condenser 294 is grounded. 40 The by-pass condenser 295 is connected between the supply line 289 and the ground.

The secondary of the audio transformer 288 is connected at one side to the control grid 296 for the type 42 tube 297, and the opposite side 45 of the secondary is grounded. The screen grid 298 of the tube 297 is connected to the supply line 299 which goes to the speaker field 300 and the other side of the speaker field goes to a second speaker field 301. The other side of the 50 speaker field 301 goes to a third speaker field 302, and the other side of the speaker field 302 goes to the 400 volt supply line 303. The primary of the output transformer 304 goes to the screen grid 298 and the opposite side is connected to the plate 305 of the tube 297. The 55 cathode of the tube 297 goes to the bias resistor 306, which bias resistor is grounded at its opposite side and the condenser 307 is connected in parallel with the bias resistor 306. The secondary 60 of the output transformer 304 is connected in parallel with the voice coil 308 of the speaker-1. The filaments of the tubes 283 and 297 are connected in parallel with the secondary of the step down transformer 309, and the primary 65 of the transformer 309 is connected in parallel with the alternating current supply 310. These tubes 283 and 297 constitute a two-stage audio frequency amplifier establishing one channel of reception.

70 Speaker-1 is actuated by the tubes 283 and 297 and their associated circuits. Speaker-2 is actuated by tubes 283a and 297a and their associated circuits, the elements of which are designated by the same numerals with the exception 75 of the addition of the letter "a" as described

with respect to the operating tubes and circuits for speaker-1. It should be noted in particular, however, that the coupling condenser 280a is connected directly with the wire 264. It should also be noted that the screen grid 288a is connected with the primary of the transformer 304a and is also connected to the supply line 298. Supply line 288 is connected with the primary of transformer 288a and also with the resistor 280. The tubes 283a and 297a constitute a second receiving channel.

Speaker-3 is actuated through the medium of the tubes 283b and 297b and the associated circuits which are similar and identical to the circuits for speaker-1 and speaker-2, and the 15 various elements are designated by the same numerals as were applied to speaker-1 and its operating circuits with the addition of the letter "b". The coupling condenser 280b is connected to the line 276—note particularly Fig. 20 20 6. The supply line 289 connects to the primary of the transformer 288b. The supply line 299 connects to the screen grid 288b of the tube 297b and the primary of the audio step up transformer 284b. The speaker-3 and its associated 25 circuits and the associated tubes 283b and 297b and their associated circuits constitute a third receiving channel.

It is not desired, however, to limit the number of receiving channels in this invention, as they 30 may be multiplied both as to transmitters and receivers at the will of the builder and operator without departing from the spirit of the invention.

The channel utilizing speaker-3 receives all 35 of the distinguishable impressions upon the carrier wave due to the fact that it is connected through the wire 276 which joins it in Figure 6 to the amplifying tube 267 which tube obtains its input through the wire 158 which wire joins the tube 267 with the wire 159 in Figure 5. The coupling is shown through the coupling condenser 157 as directly connected to the output of the diode detector 152. By coupling at this particular place any distinguishable impression upon 45 the carrier wave is readily picked up. The channels utilizing the speaker-1 and speaker-2 with their respective tubes and circuits as above described, are joined through the wires 209 and 264 respectively, designated in Figures 6 and 5. 50 Both connections lead to the circuits that reform the indistinguishable impressions that are upon the carrier wave.

The plate 311 of the tube 292 goes to one side of the high voltage secondary of the transformer 312 and the plate 313 goes to the opposite side of the high voltage secondary to the transformer 312. The center tap of the high voltage secondary of the transformer is grounded. The filaments of the tube 292 are connected in parallel with a step down winding 314 of the transformer 312. The primary of the transformer 312 is in parallel with the alternating current supply 315.

Having thus described all parts and circuits 65 in connection with my invention, I will now describe its operation.

The transmitting system (note particularly Figures 1 to 4 inclusive) is arranged for transmitting a composite carrier wave made up of a 70 plurality of individually distinct modulating frequencies. By considering also Figures 5, 6 and 7, it will be noted that means is also provided for receiving the composite carrier wave and splitting up the groups of modulating fre- 75

quencies in a manner so that they are distributed through the proper channels to individual reproducing units.

For the purpose of simplification in the following description, it should be understood that the microphone and speaker are referred to as the pick-up and reproducer units, but they may be replaced by any type of signal pick-up or reproducer without departing from the spirit of the invention, for transmitting sound, light, or any kind of signal, and it is not desired to limit the present invention to audio transmission and reception.

When speaking into the mike—1 (note Figure 1) with the battery 21 connected, there is set up a varying flow of direct current. In the secondary circuit of the microphone transformer 18 and associated parts (note Figure 1) an alternating current is produced with characteristic form of the pulsating direct current in its primary circuit. This alternating signal is applied to the grid input 24, of the tube 15. The cathode bias on tube 15 is produced by bias resistor 36 which is properly by-passed by condenser 37 so as to satisfy the demand of the type 76 tube. The plate current that flows through the primary of transformer 26 which originally was a steady D. C. flowing current from the power unit 28 will vary in accord with whatever signal characteristic is present at grid 24 in tube 15. It will be noted that amplification has also taken place between the input and the output of tube 15. The secondary circuit of transformer 26 picks up the alternating signal current and produces the characteristic signal in an amplified form upon grid 30 on tube 16. The proper bias is obtained for tube 16 through the bias resistor 34 which is properly by-passed by condenser 35 so as to satisfy the type 42 tube. The screen grid 31 maintains constant direct current potential from power unit 28. The current passing through the plate 32 is originally a steady direct current which comes through the primary of transformer 33 from power unit 28. This current varies in accord with the characteristic signal input at grid 30 in tube 16. This current is amplified once more. The signal therefore passes from mike—1 to the output transformer 33 to the conventional two-stage audio amplifier in the manner just described.

The secondary of the transformer 33 picks up the characteristic signal from the primary of the transformer 33 and supplies it to the electro-magnetic winding 40 of the electro-vibrating condenser 41. As one speaks into the microphone, the signal flowing through the electro-magnet 40 is varied in accord with the operation of the microphone and it is a well known fact that the magnetic field from such an electro-magnet will vary in accord with the signal presented within its winding. The fluctuating magnetic field set up vibrates the metal diaphragm 58 of the electro-vibrating condenser 41. The results so far produced are mechanical vibrations originally created from remote mike—1. The rest of the electro-vibrator 41 will be explained in the following.

The tube 42 is connected in an oscillating circuit supplied from the power unit 28. Steady constant oscillations are created by use of the oscillator coil 53. The tube 42 obtains its correct grid bias from the bias resistor 52, radio frequency choke 51 being inserted in this circuit to permit radio frequency current from getting into the bias supply. Cathode bias is obtained

through the oscillator coil 53. Radio frequency by-pass condenser 50 permits radio frequency currents to pass, but constitutes a bar to direct currents. The screen grid 43 of tube 42 and suppresser grid 44 of tube 42 being connected together obtain their positive potential direct current voltage from power unit 28 through resistor 45. The radio frequency by-pass condenser 46 by-passes to ground all radio frequency currents in the screen grid circuit. The plate 47 of the tube 42 obtains its direct current potential from power unit 28 through radio frequency choke 48, the purpose of this choke being to bar radio frequency from power unit 28. Steady or constant frequency oscillations are created due to this being a typical oscillating circuit since the frequency of this oscillation is determined by frequency controlling condenser 54 and the oscillator inductance coil 53. Any frequency within the range at which they are designed to operate may be selected by adjustment of the variable condenser 54. The stationary plate 55 and the vibrating plate 58 are insulated from each other by air as will be hereinafter described. Since plate 55 is stationary and plate 58 is variable, a small minute variable condenser is thus provided. This, as shown in the circuits, is connected in parallel with the controlling condenser 54, and it is well known that if either one of the condensers in parallel are changed in capacity the total capacity will be different than their original setting. It is readily seen that the capacity of the electro-vibrating condenser 41 is changed or is varied in accord with the microphone audio pick-up through the medium of the electro-magnet or field of the magnet 40.

Attention is now invited to Figure 3 from which it will be noted that a second channel of signal pick-up is illustrated, the operation of which is identical to that as described and illustrated with respect to Figure 1, with the exception that a frequency controlling condenser 54a is adjustable to a different setting so as to produce a different fundamental characteristic frequency to be used for modulating.

Note particularly Figure 4 which discloses a two-stage amplifier identical to the circuits embodying the amplifier in Figure 1, in which the tubes 15 and 16 are comprised and the operation of this circuit is identical to the amplifier circuit comprising the lower portion of the circuit illustrated in Figure 1 with the exception of course, that the frequency produced by transformer 59b does not actuate an electro-vibrator condenser. This frequency is directly used as one of the modulating frequencies.

In Figures 1, 3 and 4, it will be noted that wires 61, 63 and 113, respectively, connect to a separate suppresser grid in one of the radio frequency amplifying tubes 12, 65 and 88, respectively, of Figure 2. These coupling coils 59, 59a and 59b respectively, are in the bias circuits of the three amplifier tubes 12, 65 and 88. The bias is furnished by bias batteries 60, 60a and 65b through the coupling coils. Each coupling coil is positioned in proximity to the oscillating coil of each circuit in Figures 1 and 3, and in Figure 4 is placed in proximity to the primary of transformer 11. Any frequencies set up or variation of frequencies within the oscillating coils or primary of the transformer 11 will be induced into each coupling coil. The bias voltage passing through the coupling coils is raised or lowered according to the frequency of the sig-

nal that is picked up in the coupling coils due to the phenomena of voltage bucking, the result obtained being a varying bias voltage supply to each of the radio frequency power amplifier tubes 12, 55 and 88 so as to bias them separately and variably which is necessary for amplitude modulation by suppresser grid modulation which will be described in Figure 2. It is to be noted that in Figure 4 this is a conventional means of modulating the suppresser grid modulation, but in Figures 1 and 3 it is readily seen an unconventional method is used inasmuch as higher frequencies are used. The bias supplies for the radio frequency power amplifier tubes 12 and 15 55 will vary at a more rapid rate than the bias supply for the tube 88. For a known incoming signal of certain frequency the result produced in coupling coil 59b of Figure 4 will always have the same characteristic form. In Figure 3 where the same signal input frequency is used as in Figure 4, the output characteristic frequency in coupling coil 59a may be varied but at the will of the operator, by adjustment of variable condenser 54a. In Figure 1 the same selective flexibility is maintained and should the operator desire a tuning condenser 54 may be set to produce frequencies in coupling coil 59 close or far from frequencies obtained in 59a of Figure 3. The circuit shown in Figure 3 supplies another range of frequency which will always have the characteristic of the incoming signal. This circuit shown in Figure 3 supplies a range of selected varied frequencies which deviate in frequency in accord with the signal input in a mike—2. On the other hand, the circuit disclosed in Figure 1 supplies a still further range of frequencies selected and separated and distinct from the range of frequencies set up in the other two channels and also deviates in accord 40 with the signal input at mike—1.

My system may be used with any type of grid modulation in the R. F. power amplifier producing amplitude modulation.

The following is a description of the operation 45 of the crystal control oscillator and the radio frequency power amplifier shown in Figure 2. In the oscillator tube 66 and its associated parts and circuits, a pentode crystal oscillator circuit is shown supplied by a power unit 70. Proper 50 grid bias is supplied by bias grid resistor 79 which is properly by-passed by condenser 80. Radio frequency choke 72 bars radio frequency from the bias supply. The crystal 78 is cut to vibrate at one certain frequency and is connected 55 in the frequency controlling part of the circuit which is the control grid 76. The cathode is grounded providing the negative return, the tube is properly heated, and the proper positive direct current potential is present at the screen grid 67 and suppresser grid 68 of the tube 66. A by-pass condenser 71 by-passes to ground any radio frequency current present upon the screen grid circuit. An additional by-pass condenser 72 by-passes any radio frequency current which might 60 enter the power unit—an inductance oscillator coil 74 is in the tank circuit of the plate 73 of tube 66, and the tuning condenser being in parallel with it furnishes efficient adjustment of this tank coil. Oscillation is set up in this typical 65 oscillating circuit providing the inductance of coil 74 and the capacity of condenser 75 is such that a resonant circuit is equal to the frequency of the crystal 78. The oscillation produced is a steady alternating current. This current is 70 picked up by coupling coil 83 and with the use

of condenser 84 the proper amount is supplied to the control grids of the radio frequency power amplifier tubes 12, 65 and 88 which are connected in parallel. The control grid bias to these tubes is supplied by the bias battery 97 through the choke 96, which bars radio frequency current from the bias supply.

The filaments of the tubes 12, 65 and 88 are properly heated and the proper screen grid direct current potential is maintained on all three tubes by a screen grid parallel connection and is supplied through the radio frequency choke 92 and voltage dropping resistor 93 which in turn connects with the power unit 94. A by-pass condenser 102 is so placed as to also by-pass any radio frequency current which might enter power unit 94. The tank circuit which is comprised of inductance coil 105 and the tuning condenser 106 is capacity coupled to the plate circuits of tubes 12, 65 and 88 by condenser 104. The negative return for this amplifier is through the center tap on the secondary of the step down transformer 109 which has sufficient radio frequency by-pass through condensers 110 and 111. The radio frequency amplifier tubes being of the pentode type they do not require neutralization. With all voltages present and also an exciting frequency applied to the control grids 85, 66 and 87, these tubes will transfer and amplify the exciting energy providing the adjustment of condenser 106 is such as to produce the proper capacity for the inductance 105. The adjustments in the tank circuit will be of a resonant nature with the exciting frequency. The tank circuit will obtain radio frequency current through the radio frequency by-pass condenser 104 from the plate circuit tubes 12, 65 and 88. This current is the carrier wave current and is supplied directly to the antenna 107 by proper adjustment of the antenna condenser 108. The amplitude of this current is dependent upon the suppresser bias present on the suppresser grids 62, 64 and 114. As before stated with reference to Figure 1, the varying biasing voltages produced in wire 61 are dependent upon the units illustrated in Figure 1. Wire 61 leads to the suppresser grid 62 of the 45 tube 12, and it is readily seen that the suppresser grid voltage bias at this particular suppresser grid may be varied according to the will of the operator by adjustment of variable condenser 54 in Figure 1. Referring to Figure 3, wire 63 connects to suppresser 64 of tube 65. The coupling coil 59a supplies the varying bias voltage for the suppresser grid 64. It will also be readily seen that the operator may adjust this varying bias supply by adjustment of variable condenser 54a. Referring to Figure 4, wire 113 connects to the suppresser grid 114 in tube 88. The coupling coil 59b supplies the varying biasing voltages for suppresser grid 114. It will be readily noted that no 55 control is maintained by the operator outside of the adjusting of the incoming signal at mike—3. A radio frequency carrier wave is set up in the circuits illustrated in Figure 2 of a constant amplitude, the amplitude of which is varied by the 60 circuits and description referred to in Figures 1, 3 and 4. Each of the tubes 12, 65 and 88 produces separate characteristic impressions upon the carrier wave by varying in amount of its amplitude, and each variation is controlled by the separate 65 sending channels. A complex wave is thus produced.

The following is the operation of the receiver

The incoming carrier wave is picked up by the 75

antenna 121 and is produced in a grid circuit of the conventional radio frequency amplifier tube 124. The associated parts and circuits of tube 124 are of the conventional amplifier design and function in a conventional manner. The composite carrier wave frequency is produced in the primary of the radio frequency transformer 135. The control grid circuit of the tube 139 obtains the composite carrier wave frequency from the secondary of the radio frequency transformer 135. The radio frequency amplifying tube 139 and its associated parts and circuits are of conventional design and function in the conventional manner. The composite carrier wave frequency is produced in the primary of radio frequency transformer 107. In the tube 152 a typical diode rectifying circuit is shown which obtains its carrier frequency input from the secondary of coil 147. The various impressions upon the composite carrier wave amplitude are produced in the wire 116 due to rectification. Coupling condensers 155, 156 and 157 supply lead wires 158 and 159 with the three rectified frequencies that were originally used for modulation frequencies in the transmitting circuits. The control grid of tube 152 in its modulating section is supplied with the frequencies just mentioned through the coupling condenser 155.

Discussion will be confined to the reception of one channel of frequencies. In the plate circuit of the tube 152, one group of signal frequencies are present in the coupling coil 167. The tube 152 is a double section tube, one section being a diode rectifier, and the other section being a modulator, the associated parts and circuits being of conventional design, and functioning in a conventional manner. The tube 174 is a typical self-controlled oscillating circuit. The various parts of the circuits shown are of a conventional design and operate in a conventional manner. The frequency controlling condenser 175 determines the frequency at which this circuit will oscillate. The varying signal current present in the coupling coil 167 will have an effect upon the voltage in the oscillator coil 170 due to proximity of coupling. This will create a frequency deviation in the oscillating frequencies just described. A varying frequency in accord with the signal in coupling coil 167 is produced in the coupling coil 181. The tube 190 and its associated parts and circuits are in a conventional oscillating circuit and operate in a conventional manner, condenser 191 being the variable condenser that determines the frequency at which the circuit will oscillate. When condenser 191 is adjusted so as to produce a frequency that will equal the frequency condenser 175 has produced by its adjustment, when no signal is present in coupling coil 167, then a zero beat will be produced in the primary of the transformer 197. The zero beat is obtained by heterodyning two constant frequencies produced by the oscillating tube 174 and 190. When a signal appears in the coupling coil 167 the frequency of the oscillations produced by the tube 174 will deviate. A deviation in frequency of either of the oscillators will no longer result in a zero beat and since the frequency produced by the oscillator tube 190 is constant, the beat signals produced in the primary of the transformer 197 will be equal to the sums and the differences of the two frequencies at any one instant. The sums of the frequencies being useless to this invention due to the fact that the equipment following is not responsive to those frequencies. This leaves only the differences as useful frequencies. As stated in connection with the

transmitting circuits, the indistinguishable modulating frequencies are varied or deviate in accord with the microphone pick-up. Therefore, the signal current present in the coupling coil 167 varies in accord with the microphone pick-up. If this variation is in accord with the microphone pick-up, then the beat frequency produced in the primary of transformer 197 will also vary and be equal to the frequencies picked up by the microphone. The secondary of transformer 197 produces to the grid circuit of the conventional high gain audio frequency amplifying tube 119 a signal of audible frequencies. The associated parts and circuits in connection with the tube 199 are of conventional design and function in a conventional manner. The lead wire 209 goes to the coupling condenser 280 in Figure 7. This coupling condenser couples the audio frequency output of tube 199 to the control grid input of audio frequency amplifying tube 283. Tube 283 and its associated parts and circuits is a conventional audio frequency amplifier and functions in a conventional manner. The audio frequency signal is introduced into the primary of the transformer 288, the secondary of transformer 288 feeds the audio signal into the control grid circuit of tube 197. The tube 297 and its associated parts and circuits is a conventional audio frequency amplifier and functions in the conventional manner. The primary of transformer 304 obtains the audio signal in a greatly amplified form. The secondary of the output transformer 304 feeds the voice coil 308 of speaker-1. Speaker-1 is a conventional speaker and operates in a conventional manner.

Referring to Figure 5, the circuits disclosed constitute a second receiving channel which may be duplicated, and also a third receiving channel. The second receiving channel made up of tubes 214, 231, 254 and 245, are identical and function in the same manner as the circuits and tubes just mentioned, namely, tubes 152, 174, 190 and 199, respectively. The second receiving channel obtains the input signal through the wire 159 which is connected in Figure 5 to the coupling condenser 156. The signal output in the second receiving channel is sent through wire 264 to the coupling condenser 280a in Figure 7. The frequency controlling condensers 232 and 246 are adjustable in the same manner as described above but so as to perform in a manner so that the beat frequency output in the primary of transformer 252 is of the proper audio frequencies. It will readily be seen that there is but one proper adjustment of each condenser. It is shown that each of the receiving channels 1 and 2 are tunable so as to receive separate and individual microphone pick-ups. Now, referring to Figure 7, the coupling condenser 280a feeds the two-stage audio amplifier which is conventional, and an exact duplicate of the two-stage audio amplifier just described and located directly above in Figure 7, consisting of the tubes 297 and 283. The conventional speaker-2 produces the output of this audio frequency amplifier. A third channel is used to reproduce any distinguishable impression upon the composite carrier wave that may be present. Referring to Figure 5, the coupling condenser 157 feeds the wire 159 which leads to the control grid of the tube 267 in Figure 6. This tube and its associated parts and circuits is a conventional high gain audio frequency amplifier and functions in a conventional manner. The output of this tube goes to the wire 276 which goes to the coupling condenser 280b in Figure 7. This coupling con-

denser feeds the input of a two-stage audio frequency amplifier i. e. tubes 283b and 297b. This amplifier and its associated parts and circuits are conventional and operate in a conventional manner. The conventional speaker-3 reproduces the output in a conventional manner. The conventional power supply for all units and circuits in Figure 7 is shown at the bottom of the diagram and consists of the tube 292 and its associated parts and circuits.

Summary

By carefully considering Figures 8 and 9, it will be noted that general diagrams are shown illustrating the transmitting and receiving system, and for convenience I will describe the passage of an audio wave from the microphone to the loud speaker of the transmission and receiving system as follows:

20 Referring to Figure 9, sound waves are picked up by the microphone 17, a pulsating direct current as described by wave form 1 is created, the amplifier D amplifies wave form 1, and produces an alternating current as shown by wave form 2. The oscillator F creates a constant alternating frequency, as shown by wave form 5. The wave form 2 operates the electro-vibrating condenser E which in turn frequency modulates wave form 5 so as to produce wave form 3. Wave form 3 is constant in amplitude but varies in frequency in accord with wave form 2. Crystal oscillator H creates constant alternating current frequency, as shown by wave form 6. Wave form 6 excites the power amplifier G and the amplified output of amplifier G is of the same frequency as oscillator H. The varying frequency wave form 3 amplitude modulates power amplifier G so as to produce wave form 4. Wave form 4 is the composite carrier wave of the same frequency as crystal oscillator H and is emitted by antenna 107.

Referring to Figure 8, the composite carrier wave created in Figure 9 is received by the antenna 121, and is of a very weak amplitude shown by wave form 310. Radio frequency amplifier J amplifies wave form 310 and produces wave form 311 of greater amplitude. Radio frequency amplifier K amplifies wave form 311 so as to produce wave form 312 of still greater amplitude. It is noted that wave form 312 has the same identical characteristics that the original composite carrier wave had. Demodulator B rectifies wave form 312 and produces all the impressions that vary its amplitude and is shown by wave form 313. Oscillator M creates an alternating current frequency, as shown by wave form 314 and the wave form 313 is of a direct current but pulsates at a fairly high frequency rate. The wave form 314 is frequency modulated through the modulator N by wave form 313 and wave form 315 is produced as the result. Wave form 315 has a constant amplitude but varies in frequency in accord with the modulating signal wave form 313. A second oscillator O creates an alternating current frequency as shown by wave form 317. The frequency of wave form 317 is equal to the frequency of wave form 314. When there is no modulating signal wave form 313, zero beat is obtained between these two frequencies by method of heterodyning. When frequency modulation takes place in modulator N wave form 315 deviates and produces a beat frequency by method of heterodyning with wave form 317, in the mixer of demodulator P. The 75 beat frequency created is shown by wave form

316 and is of audio frequency. Audio frequency amplifier R amplifies wave form 316 so as to produce wave form 318 and actuates the reproducing speaker S, which creates the sound waves.

The above summary constitutes a description of one channel of transmission and receiving communication. It should be understood that these channels may be multiplied so that a plurality of channels may be utilized for transmission and receiving purposes over the same carrier wave at the same time, the present summary merely being typical of the functioning of the various elements of the transmission and receiving system.

The above summary also constitutes an ideal description of a secret transmitter and receiving system.

By referring to Figures 10 to 12 in detail and by noting the previous description, it will be seen that the particular type of electro-vibrating condenser which I use in conjunction with my system comprises a casing 412 previously described, within which casing 412 are mounted the electro-magnets 40 which electro-magnets are insulated from the casing 412. This casing 412 is provided with a binding post 320 which is grounded. The wires 321 and 322 which lead from the electro-magnets 40 pass through the insulated grommets carried by the casing 412 and are connected to the secondary of the transformer 33, such as is indicated in Figure 1, or 33a as is indicated in Figure 3. This transformer constitutes the output of the audio amplifier. A diaphragm plate 58 preferably made of tin or any flexible magnetic material is secured to the top edge of the casing 412 and a non-magnetic plate 55 is spaced from the diaphragm plate 58 by means of an insulated washer or gasket 323. An insulated cap 324 is threaded over the top of the casing 412 to bind the parts in position. A binding post 325 extends through the cap 324 and this is connected to the wire 9, as shown in Figure 1, or 9a as shown in Figure 3, depending upon the circuit in which the electro-vibrating condenser is located.

The electro-magnets 40 comprise preferably iron cores and suitable insulated windings. A magnetic field is set up from the output of the audio amplifier connecting at wires 321 and 322. The magnetic field varies in proportion in intensity in accord with the output of the audio amplifier. An intense magnetic field vibrates the diaphragm 58 with greater amplitude causing greater frequency deviation in the oscillator circuits of Figures 1 and 3. The stationary plate 55 and the vibrating plate 58 are spaced and insulated by the insulated washer 23 so as to produce a large area condenser with small capacity and yet so that the diaphragm plate 58 and plate 55 do not touch each other when vibrating according to suitable adjustments of the audio amplifier. The stationary plate 55 and the vibrating plate 58 are given a coating of high frequency insulating lacquer as prevention against becoming a shorted condenser in the event that they should come into contact or become too close together. The space between the diaphragm plate 58 and the plate 55 may be either air filled or constitute a vacuum without departing from the spirit of the invention. The insulating lacquer is not placed on the 70 part of the diaphragm 58 that rests upon the casing. It is at this point that the diaphragm obtains a grounded connection.

Having described the invention, what I claim as new is:

1. An electro-vibrating condenser comprising a casing, electro-magnets mounted within and insulated from said casing, means for energizing said magnets, means for grounding the casing, 5 means for closing one end of the casing, an electrical connection with said means, and a diaphragm of magnetic material adapted to be actuated by said magnets and spaced from said means for closing said casing.
- 10 2. An electro-vibrating condenser comprising a casing of conducting material, electro-magnets carried by and insulated from said casing, a closure cap of insulated material removably closing one end of said casing, a conducting plate carried by said cap, a diaphragm of magnetic material spaced from said plate and grounded upon said casing, insulating means interposed between the diaphragm and the first mentioned plate whereby the diaphragm will be spaced and insulated from said first mentioned plate, and an electrical connection for said first mentioned plate, said diaphragm being of flexible material and free to vibrate between the electro-magnets and said first mentioned plate.
- 15 20 25 3. A system of the class described comprising means for setting up and transmitting a carrier wave, a frequency modulated oscillator for producing modulated indistinguishable frequencies in the carrier wave, an electro-vibrating condenser, a typical two-stage amplifier and a signal pick-up, a frequency controlling circuit actuating said oscillator, an output for said two-stage amplifier, said electro-vibrating condenser coupling said output of said two-stage amplifier to the frequency controlling circuit of said oscillator, an input for said amplifier coupled to the signal pick-up unit, a carrier wave receiving and rectifying means, and a carrier wave re-forming means for re-forming the carrier wave and rendering the frequencies distinguishable.
4. A system of the class described comprising means for setting up and transmitting a carrier wave, a frequency modulated oscillator for producing modulated indistinguishable frequencies in the carrier wave, an electro-vibrating condenser, a typical amplifier and a signal pick-up, a frequency controlling circuit actuating said oscillator, an output for said amplifier, said electro-vibrating condenser coupling said output of said amplifier to the frequency controlling circuit of said oscillator, an input for said amplifier coupled to the signal pick-up unit, a carrier wave receiving and rectifying means, and a carrier wave re-forming means for re-forming the carrier wave and rendering the frequencies distinguishable.

PAUL SAYLOR, JR.
